CARBURETOR

Cornelius F. Hoyt, Rochester, N. Y.

Application April 11, 1934, Serial No. 720,085

13 Claims. (Cl. 219—38)

The object of this invention is to provide a carburetor with electrically heated spray nozzles therein that are adapted to heat the fuel of the carburetor as it passes through the nozzles to 5 the intake manifold.

Another object of the invention is to provide a carburetor with spray nozzles therein that are adapted to be heated by an electric current that is controlled by a rheostat, which in turn 10 is operated by a thermostat on the exhaust manifold.

Another object of the invention is to provide electrically heated coils inside of the spray nozzles of a carburetor, by which the fuel is heated 15 directly as it passes through the nozzles to the intake manifold.

Another object of the invention is to preheat the fuel oil before entering the carburetor, by leading the fuel line from the supply tank 20 through a heating chamber on the exhaust manifold of the engine.

These and other objects of the invention will be illustrated in the drawing, described in the specification, and pointed out in the claims at 25 the end thereof.

In the drawing:

Figure 1 is a side elevation of the engine, together with the manifold, carburetor, and parts 30 associated therewith.

Figure 2 is a section on the line 2x—2x of Figure 3, showing the combined rheostat and thermostat.

Figure 3 is a side elevation of the rheostat, as viewed from the right in Figure 2.

Figure 4 is an elevation of the thermostat, as viewed from the left in Figure 2.

Figure 5 is an enlarged fragmentary sectional view of a so-called Zenith carburetor, showing the spray nozzles therein.

Figure 6 is an enlarged sectional view of the spray nozzles, showing the heating coils therein.

Figure 7 is a section on the line 7x—7x of Figure 1, showing the exhaust manifold in section and the end of the heating chamber in elevation.

In the drawing like reference numerals indicate like parts.

In the drawing reference numeral 1 indicates an automobile engine having an intake manifold 2 thereon to which is attached the carburetor 3.

The carburetor 3 is of the so-called Zenith type and is adapted to mix air and fuel oil, or air, fuel oil and gasoline, or air and gasoline. The carburetor 3 has two tapered spray nozzles 4 and 5 therein that are more or less selectively operated, one for low speeds and the other for

high speeds. Inside of the spray nozzles 4 and 5 are provided the helical resistance coils 6 and 7 that heat up upon the flow of electric current therethrough. The helical resistance coils 6 and 7 are in the direct path of the fuel as it 5 passes from the carburetor 3, and are adapted to heat the fuel directly, and cause the fuel to vaporize more readily as it passes from the carburetor 3 to the intake manifold 2 on its way to the cylinders. The upper ends of the helical 10 resistance coils 6 and 7 are connected to each other, as shown in Figure 6, and the electrical current coming from the wire 8 is adapted to flow up through the coil 6, to the coil 7, and then down through the coil 7, where it is 15 grounded on the spray nozzle 5. The helical coils are insulated from the spray nozzles 4 and 5 by the tapered sleeves 9 and 10, which are preferably made of mica.

The wire 8 and the wire that connects the 20 helical resistance coils at the top are insulated from the spray nozzles 4 and 5 by a cement filler 11 that not only insulates the wires from the spray nozzles, but also forms an air-tight joint between the spray nozzles and the wires. 25

To control the flow of current to the helical resistance coils 6 and 7, I provide the rheostat 12 operated by a thermostat 13 provided in a casing 14 that is suitably attached to the exhaust 30 manifold 15.

As shown in Figure 2, the casing 14 containing the thermostat 13 is open at one end, which end is adapted to be fastened to the exhaust manifold 15 with the thermostat exposed to the exhaust manifold. As the exhaust manifold 35 heats up, it also heats up the thermostat 13, causing the thermostat to expand and turn the shaft 16, which extends through the casing and has a fibre arm 17 at the other end thereof that is fastened to the shaft 16 by a set screw 40 18. The arm 17 is angularly adjustable on the shaft 16 by the set screw 18, which permits the setting of the arm 17 on the shaft 16 to the correct angular position with reference to the thermostat. Another arm 19 is mounted on the 45 shaft 16 and insulated therefrom, which makes engagement at one end with the resistance coil 20 of the rheostat. This arm 19 can move freely on the shaft 16 independent of the movement of the shaft 16, as will be more fully described 50 hereinafter.

The arm 19 has a tension spring 21 attached thereto that pulls one end of the arm downward, and causes the opposite end of the arm to normally engage the stop 22 on the arm 17. The 55

arm 17, which moves with the shaft 16, that is controlled by the thermostat 13, controls the position of the arm 19 and regulates the amount of electrical current that passes to the helical resistance coils 6 and 7. The movements of the arms 17 and 19 are limited by the pins 23 and 24 provided on the rheostat 12.

To operate the engine more efficiently at high speeds and permit the rheostat 12 to supply a more generous supply of electrical current to the helical resistance coils 6 and 7 regardless of the temperature of the exhaust manifold 15, I provide the following arrangement: Attached to the arm 19 is a link or rod 25 having an eye at the lower end, through which the accelerator rod 26 passes. The accelerator rod 26 has a collar 27 thereon that is fastened to the accelerator rod by a set screw 28 which permits the adjustment of the collar either forward or back on the accelerator rod 26. When the accelerator rod 26 is pushed downward to allow more fuel to enter the engine, the collar 27 will engage the spring 29 that is placed between the link 25 and collar 27 and cause the spring to compress slightly and move the link 25 downward, throwing the end of the arm 19 that is engaged by the link 25 upward, and moving the end that engages the resistance coil 20 downward or to the left as shown in Figure 1. The arm 17 will remain in the position that is determined by the thermostat, and when the accelerator rod 26 is raised to a position in which the collar 27 no longer engages the spring 29, the tension spring 21 will immediately draw the end of the arm 19 that is engaged by the link 25 downward, and cause the end that engages the resistance coil 20 to move upward until it engages the stop 22 on the arm 17, and the arm 19 will again be controlled by the position of the arm 17 that is controlled by the thermostat.

On top of the exhaust manifold 15 is placed a heating chamber 30 having a front, a back, a top, and two ends, but no bottom. One of the ends has an opening 31 therein that is closed by a valve 32 pivoted at 33. The valve has a handle 34 thereon by which the valve may conveniently be opened or closed manually. The fuel line 35 passes through the heating chamber 30 and makes contact with the exhaust manifold as it passes therethrough. When the engine is running on fuel oil, the opening in the end of the heating chamber will be closed by the valve and the heat from the exhaust manifold 15 will heat the air in the heating chamber and the fuel that is passing through the fuel line in the heating chamber 30 will not only be heated by the exhaust manifold, but also by the hot air surrounding the fuel line 35. When the engine is running on gasoline it is preferable to have the opening 31 open to permit cool air to circulate around the fuel line in the heating chamber to prevent the gasoline from becoming vaporous before it reaches the carburetor.

In operation, before the engine starts, and when the parts are cold, the thermostat has caused the arms 17 and 19 to engage the stop 23. The carburetor is filled with the desired fuel. The ignition switch 36 is closed, which permits the electrical current of the battery 37 to flow to the arm 19 through the resistance coil 20, the wire 8, and the helical resistance coils 6 and 7, which causes the coils to heat up. The engine is then turned over, drawing in a charge heated by the resistance coils 6 and 7, which charge will explode and drive the engine. The coils 6

and 7 remain fully heated up until the exhaust manifold becomes heated. The thermostat 13 then becomes heated and moves the arm 17 to the right, as shown in Figure 1, permitting the arm 19 to move also to the right, building up a greater resistance in the resistance coil 20 as it moves to the right, and allowing a correspondingly smaller amount of electrical current to flow to the helical resistance coils 6 and 7, which reduces the amount of heat generated by the helical resistance coils 6 and 7. The further the arm 19 moves to the right, the less heat the resistance coils 6 and 7 will generate.

I claim:

1. A carburetor for an internal combustion engine, having a spray nozzle therein, said nozzle consisting of a single tube through which the liquid fuel passes, a coil of resistance wire placed inside of said tube and submerged in the liquid fuel in the tube and making direct contact with and heating the fuel therein, insulation interposed between the outside of said coil of wire and the inside of said tube, a rheostat adapted to control the flow of electric current through said resistance wire in said tube, a thermostat connecting to said rheostat by which said rheostat is normally operated.

2. A carburetor, for an internal combustion engine, having a spray nozzle therein, said nozzle having a passageway for liquid fuel therein, a coil of resistance wire submerged in the liquid fuel in said passageway and making direct contact with and heating the fuel therein, a rheostat adapted to control the flow of electrical current through said resistance wire in said spray nozzle, a thermostat connected to said rheostat by which said rheostat is normally operated, means for manually operating said rheostat independently of said thermostat.

3. A carburetor, for an internal combustion engine, having spray nozzles therein, said nozzles having a passageway for liquid fuel therein, a heating element located in said passageway for heating the liquid fuel therein, a rheostat adapted to control the flow of electrical current to said heating element in said spray nozzles, said rheostat comprising a body, a resistance coil on said body, a shaft passing through said body, and an arm on one of said shafts that is adapted to make contact with said resistance coil, a thermostat on the other end of said shaft that is adapted to turn said shaft and said arm to control the flow of electrical current through said resistance coil.

4. A carburetor, for an internal combustion engine, having spray nozzles therein, said nozzles having a passageway for liquid fuel therein, a heating element located in said passageway for heating the liquid fuel therein, a rheostat adapted to control the flow of electrical current to said heating element in said spray nozzles, said rheostat comprising a body, a resistance coil on said body, a shaft passing through said body, an arm fastened to said shaft having a stop on one side thereof, a second arm on said shaft that is freely rotatable thereon that is adapted to make contact with said resistance coil at one end thereof, a spring fastened to the other end of said last named arm, said spring being adapted to cause said freely rotatable arm to normally engage the stop on said first named arm and move with said first named arm, a thermostat on the other end of said shaft, that is adapted to turn said shaft and the arms thereon

to control the flow of electrical current through said resistance coil.

5. A carburetor, for an internal combustion engine, having spray nozzles therein, said nozzles having a passageway for liquid fuel therein, a heating element located in said passageway for heating the liquid fuel therein, a rheostat adapted to control the flow of electrical current to said heating element in said spray nozzles, said 10 rheostat comprising a body, a resistance coil on said body, a shaft passing through said body, an arm fastened to said shaft having a stop on one side thereof, a second arm on said shaft that is freely rotatable thereon that is adapted 15 to make contact with said resistance coil at one end thereof, a spring fastened to the other end of said last-named arm, said spring being adapted to cause said freely rotatable arm to normally engage the stop on said first named arm, a thermostat 20 and move with said first named arm, a thermostat on the other end of said shaft, that is adapted to turn said shaft and the arms thereon to control the flow of electrical current through said resistance coil, means for operating said 25 freely rotatable arm independently of said first named arm.

6. In an internal combustion engine, the combination of an exhaust manifold, a carburetor, a heating chamber on said exhaust manifold having an opening at one end thereof, a valve on 30 said heating chamber for controlling the size of said opening, a fuel line, a part of said fuel line being located in said heating chamber whereby the fuel contained therein is heated as it passes 35 to the carburetor.

7. A carburetor, for an internal combustion engine, having a spray nozzle therein, said nozzle consisting of a single tube through which the liquid fuel passes, a coil of resistance wire placed 40 inside of said tube and submerged in the liquid fuel in the tube and making direct contact with and heating the fuel therein, insulation interposed between the outside of said coil of wire and the inside of said tube.

45. 8. A carburetor, for an internal combustion engine, having a spray nozzle therein, said nozzle consisting of a single tube through which the liquid fuel passes, a coil of resistance wire placed inside of said tube and submerged in the liquid 50 fuel in the tube and making direct contact with and heating the fuel therein, insulation interposed between the outside of said coil of wire and the inside of said tube, means for controlling the supply of electric current to said coil of wire.

55. 9. A carburetor, for an internal combustion engine, having an electrically heated spray nozzle therein, a rheostat adapted to control the flow of electrical current to said electrically heated spray nozzle, said rheostat comprising a body, a resistance coil on said body, an arm on 60 said body adapted to engage said resistance coil, a link connected to the other end of said arm, a rod engaging said link, said rod being adapted to move said link to cause said arm to rock and 65 vary the flow of electrical current through said resistance coil.

70. 10. A carburetor, for an internal combustion engine, having an electrically heated spray nozzle therein, a rheostat adapted to control the flow of electrical current to said electrically heated spray nozzle, said rheostat comprising a body, a resistance coil on said body, an arm on 75 said body adapted to engage said resistance coil, a pin on said body, a spring for normally caus- tng said arm to engage said pin, a link connected

to the other end of said arm, said link having an eye at the other end thereof, a rod passing through said eye, a collar on said rod, said collar being adjustable up and down on said rod, said collar being adapted to move said link at a predetermined time upon the downward movement 5 of said rod, causing said arm to rock away from said pin and vary the flow of electrical current through said resistance coil.

11. A carburetor, for an internal combustion 10 engine, having an electrically heated spray nozzle therein, a rheostat adapted to control the flow of electrical current to said electrically heated spray nozzle, said rheostat comprising a body, a resistance coil on said body, a shaft passing 15 through said body, an arm on said shaft making contact with said resistance coil, a thermostat at the other end of said shaft adapted to turn said shaft and said arm to vary the flow of electrical current through said resistance coil, means for 20 manually operating said arm independently of said thermostat.

12. A carburetor, for an internal combustion engine, having an electrically heated spray nozzle therein, a rheostat adapted to control the flow of 25 electrical current to said electrically heated spray nozzle, said rheostat comprising a body, a resistance coil on said body, a shaft passing through said body, an arm passing through said shaft having a stop on one side thereof, a second arm 30 on said shaft freely rotatable thereon making contact with said resistance coil at one end thereof, a spring fastened to the other end of said second named arm, said spring causing 35 said freely rotatable arm to normally engage the stop on said first named arm and move with said first named arm, a thermostat on the other end of said shaft adapted to turn said shaft and the arms thereon to control the flow 40 of electrical current through said resistance coil, a link on said second named arm, a rod engaging said link, said rod being adapted to move said link to cause said second named arm to rock and control the flow of electrical current through said resistance coil independently of the oper- 45 ation of said thermostat.

13. A carburetor, for an internal combustion engine, having an electrically heated spray nozzle therein, a rheostat adapted to control the flow of 50 electrical current to said electrically heated spray nozzle, said rheostat comprising a body, a resistance coil on said body, a shaft passing through said body, an arm passing through said shaft having a stop on one side thereof, a second arm 55 on said shaft freely rotatable thereon making contact with said resistance coil at one end thereof, a spring fastened to the other end of said second named arm, said spring causing 60 said freely rotatable arm to normally engage the stop on said first named arm and move with said first named arm, a thermostat on the other end of said shaft adapted to turn said shaft and the arms thereon to control the flow of 65 electrical current through said resistance coil, a link on said second named arm, said link having an eye at the other end thereof, a rod passing through said eye, a collar on said rod, said collar being adjustable up and down on said rod, said collar being adapted to move said link at a predetermined time upon the downward movement 70 of said rod, causing said second named arm to rock and vary the flow of electrical current through said resistance coil independently of the operation of said thermostat.
